ABSTRACT OF THE DISCLOSURE

This disclosure describes an adjustable rotary switch suitable for use with a power filing cabinet for storing records in separate groups wherein the groups are movable through a continuous orbit of travel. The switch comprises a sprocket, a commutator disc, and a brush holder generally aligned about the axis of a stud. In addition, a guide block bracket is attached to the commutator disc and coacts with a guide block attached to the sprocket so as to vary the lateral location of the commutator disc with respect to the brush holder. There are various conducting regions on the face of the commutator disc that faces the brush holder. These regions co-act with brushes mounted in the brush holder. Predetermined portions of the conducting regions are separated by a V-shaped outwardly extending region of an insulating material. The movement of the commutator disc with respect to the brush holder by the guide block—guide block bracket co-action varies the length of time it takes for a brush to pass over the V-shaped insulating region or "stop space." In this manner, the period of time that a brush resides in the stop space while it is stopping is varied.

BACKGROUND OF THE INVENTION

This invention relates to switches suitable for use with filing cabinets used to store groups of records wherein the groups are movable through a continuous orbit of travel. In general, a continuous orbit of travel filing cabinet includes a continuous loop mechanism, such as a conveyor, that is driven by a motor. The groups of records to be stored are attached to the conveyor by any suitable means such as by lying on trays. The conveyor can move in a horizontal or a vertical plane, however, it preferably moves in a vertical plane.

Associated with the driving motor is a rotary switch of the type herein disclosed that determines the direction of rotation of the motor when it is desired to move a remote tray from a stopped position to the tray access opening in the filing cabinet. That is, because the trays are on a continuous loop conveyor they can be moved in either direction to reach the access opening. For rapid response, it is desirable that the distance moved be the shortest possible distance. The rotary switch associated with the driving motor performs this function.

A simple bi-directional, rotary switch will not perform the foregoing function because certain operational parameters vary to cause misalignment between the trays and the access opening when a tray is delivered to the opening. For example, variations occur between simulated loads used at the factory when preliminary adjustments are made and loads provided by the customer. In addition, as the conveyor and its associated mechanism is used it becomes less "tight," making for a greater ease of movement. In either case the coasting factor varies. That is, there is a point at which the driving motor must be turned off, thereafter, the trays coast a short distance until their momentum reduces to zero. And, this coasting factor varies because of load variations and age as previously discussed.

The prior art has attempted to solve the variable coast-

2

ing problem by providing a variable "stop space" between the conductors of the rotary switches. One prior art switch utilizing this approach to solve the problem is described in U.S. Patent 3,198,894 issued to Newton J. Krug. While that patent discloses a switch, somewhat similar to this invention, for aligning a filing cabinet system so that the cabinet's trays come to rest in alignment with the access opening in the cabinet, it has certain disadvantages. Specifically, the Krug switch is difficult to adjust. To be adjusted the switch requires loosening a set screw and moving a worm screw to vary the alignment between a pair of discs, and the tightening of the set screw. In addition, the screws are located in a rather limited space and are adjusted with an Allen wrench. Hence, the switch is difficult to adjust for various reasons and requires a plurality of specialized parts. Moreover, the switch structure per se is rather complicated.

Therefore, it is an object of this invention to provide a new and improved rotary switch suitable for use with a continuous orbit of travel filing cabinet.

It is also an object of this invention to provide a new and improved rotary switch that is uncomplicated and, therefore, easy to adjust.

It is a further object of this invention to provide a new and improved rotary switch that is uncomplicated, inexpensive, and suitable for use with a continuous orbit of travel filing cabinet to align a cabinet tray with the access opening in the cabinet when the tray comes to rest at the opening.

SUMMARY OF THE INVENTION

In accordance with a principle of this invention a new and improved rotary switch suitable for use with a continuous orbit of travel filing cabinet is provided. The switch generally comprises a commutator disc having conductors on one side. Mounted adjacent to the commutator disc is a brush holder. The commutator disc and the brush holder are axially aligned about a stud for rotation with respect to each other. In addition, means are provided for laterally moving the commutator disc with respect to the brush holder.

In accordance with a further principle of this invention, the means for moving the commutator disc with respect to the brush holder includes a guide block bracket attached to the commutator disc about the stud. Mounted on the stud is a sprocket and attached to the sprocket is a guide block. The commutator disc and the guide block bracket have an axis that can be moved with respect to the axis of the stud and the other elements. The stud and the other elements having a fixed axis. Hence, the commutator disc is movable with respect to the brush holder so as to vary the location of the brushes held by the brush holder with respect to the commutator disc. The movement is to various fixed positions.

In accordance with still another principle of the invention, generally ring-shaped conductors are located on the face of the commutator disc facing the brushes and, certain portions of the conductors are separated by an outwardly extending V-shaped insulating region. Therefore, as the commutator disc is moved with respect to the brush holder, the point at which the brushes passing over the V-shaped insulating region start into the insulating region is varied. In this manner, an alignment control is provided. More specifically, when a particular brush reaches the V-shaped insulating region the motor causing tray movement shuts off and the desired tray coasts into position with the access opening in the cabinet. However, the amount of coasting varies with tray load and other factors. The ability to vary the brush—V-shaped insulating region contact point varies the motor turn of point to allow more or less coasting as is necessary for a particular machine when it carries a particular load. Hence, the invention

provides an apparatus for aligning the trays with the access opening in the filing cabinet regardless of load or other factors.

It will be appreciated that the invention provides a less complicated and a more easily adjusted rotary switch than is provided by the prior art, such as the switch illustrated in the Krug patent. Specifically, only a single commutator disc is required as opposed to a pair of commutator discs. It is not necessary to provide a complex movement of one disc with respect to another disc to increase or decrease the size of the stop space. All that is required is an uncomplicated lateral movement of a guide block bracket with respect to a guide block. Preferably, this movement is provided by a single positioning screw that rotatably, but fixedly, attached to the guide block bracket. The positioning screw moves into and out of the guide block to provide the desired movement of the guide block bracket with respect to the guide block. Hence, this invention provides a less complex and more easily adjusted rotary switch than is provided in the prior art. Further, because the switch is less complex, it is more economical to manufacture.

BRIEF DESCRIPTION OF THE DRAWINGS

The foregoing objects and many of the attendant advantages of this invention will become more readily appreciated as the same becomes better understood by reference to the following detailed description when taken in conjunction with the accompanying drawings wherein:

FIG. 1 is a side view of the invention;

FIG. 2 is a top view of the invention;

FIG. 3 is a face view of the conductive surface of one commutator disc suitable for use in the invention; and,

FIG. 4 is a face view of the conductive surface of a second commutator disc suitable for use in the invention.

DESCRIPTION OF THE PREFERRED EMBODIMENTS

FIG. 1 is a side view of the switch of the invention and generally comprises: a stud 11; a sprocket 13; a guide block 15; a guide block bracket 17; a commutator disc 19; a brush holder 21; a collar 23; and a bracket 25. The stud has a lower region about which, as hereinafter described, the brush holder 21, the collar 23, and the bracket 25 are mounted for non-rotation and an upper region about which the commutator disc 19, the guide block bracket 17, the guide block 15, and the sprocket 13 rotate.

Starting at the lower end of the stud, the elements of the switch are mounted about the stud in the following manner. A lower nut 27, is attached to the stud 11. Located above the lower nut 27 is a washer 29, and located above the washer 29, is a mounting bracket 25. The mounting bracket 25 has a generally U-shaped cross-sectional configuration with outwardly extending arms. Preferably, holes extend through the arms so that the mounting bracket can be mounted on any suitable support member.

Located above the bracket 25 is the collar 23 and located above the collar 23 is the brush holder 21. A plurality of brushes 31 extend through the brush holder 21, however, for purposes of clarity only two brushes are illustrated in FIG. 1. Preferably, the brush holder is formed of a sheet of dielectric material.

The brushes 31 that extend through the brush holder 21 from one surface to the other have pointed but slightly flat upward ends and flat lower ends. Preferably, the brushes have cylindrical cross-sectional configurations, however, they can be square or can have any other regular cross-sectional configuration as desired. One end of a curved, metal spring 33 presses against the flat lower ends of the brushes 31 to force them upwardly as illustrated in FIG. 1. The other end of the curved spring is attached to the brush holder 21 by a cap screw 35. At-

tached by the cap screw 35 to the curved spring is a metal terminal 37. The curved spring is separated from the brush holder 21 by a washer 39.

Mounted above the brush holder 21 about the stud 11 is a first washer 41 and above the first washer 41 is a retaining ring 43 mounted in a groove in stud 11. The lower nut presses the brush holder 21, the collar 23 and the bracket 25 against the retaining ring 43 so that they do not rotate about the stud. Mounted above the retaining ring 43 is the commutator disc 19. Located on the lower surface of the commutator disc 19 are a plurality of electrical conductors of various configurations. The location and shape of two preferred conductor configurations are illustrated in FIGS. 3 and 4 and hereinafter discussed.

Mounted above the commutator disc 19 and fixedly attached thereto is the guide block bracket 17. The guide block bracket 17 is preferably formed of a flat piece of sheet metal and has an upwardly extending arm 45 illustrated in FIG. 1. The guide block bracket 17 is fixedly attached to the commutator disc 19 by a plurality of cap bolts 47. Mounted above the guide block bracket and in an aperture 46 (FIG. 2) in the guide block bracket is the guide block 15. The guide block is a generally block shaped element preferably formed of a reasonably hard metal or plastic material. The aperture 46 in the guide block bracket 17 is large enough to allow the guide block bracket to move back and forth (laterally) with respect to the guide block for the hereinafter described purpose.

Extending through an aperture in the arm of the guide block bracket 17 is an adjustment bolt 49. The adjustment bolt screws into threads located in the left side of the guide block 15 as viewed in FIGS. 1 and 2. The adjustment bolt 49 is held fixed in the aperture in the arm of the guide block bracket 17 by a washer 51 and a retaining ring 52. The retaining ring 52 fits into a groove in the adjustment bolt 49. A washer shaped spring 54 is mounted between the head of the adjustment bolt and the arm 45. However, the adjustment bolt is rotatable in the aperture. Hence, as the bolt 49 is turned, it forces the guide block bracket 17 to move forward or backward with respect to the guide block 15 depending upon the direction of turning. It should be noted from FIG. 1 that the bottom portion of the guide block 15 is separated from the commutator disc 19 by a slight amount. This slight amount provides freedom of movement between the guide block 15 and the commutator disc when the adjustment bolt 49 is turned.

Mounted above the guide block 15 and fixedly attached thereto by a plurality of bolts 53 illustrated in FIG. 2 is the sprocket 13. It is to be understood that the sprocket is driven by the motor that moves the trays of the continuous orbit of travel filing cabinet so that there is synchronization between the movement of the commutator disc and the trays. Located above the sprocket 13 is a washer 55 pressed against the sprocket by a nut 57 threaded onto the stud 11.

By mounting the elements of the switch in the foregoing manner, the commutator disc is rotatable with respect to the brush holder. In addition, the lateral location of the commutator disc with respect to the brush holder can be varied by the co-action between the guide block bracket and the guide block.

FIGS. 3 and 4 illustrate commutator discs suitable for use in the embodiment of the invention illustrated in FIGS. 1 and 2. Preferably, the discs are formed of a substrate of nonconductive insulating material are electrically conductive patterns of the type illustrated in FIGS. 3 and 4 are formed onto one surface of the substrate. These conductive patterns may be formed by vacuum depositing a conductive layer onto the surface of the substrate, for example. Thereafter, a conventional photo-engraving-etching procedure is used to remove undesired metal areas and form the resultant pattern. Finally, in-

sulating regions are formed in predetermined areas between portions of the conductive pattern.

The commutator disc illustrated in FIG. 3 comprises a flat, circular substrate 61. Outer and inner ring shaped, electrically conductive patterns 63 and 65 are formed on one surface of the substrate 61. The conductive patterns are raised above the surface of the substrate. The outer edge of the outer pattern 63 and the inner edge of the inner pattern 65 are both circular and axially aligned with the center of the circular substrate 61. In addition, the outer edge of the outer pattern is separated from the outer edge of the substrate by a narrow, circular insulating band 62 and the inner edge of the inner pattern is separated from the center of the substrate by a rather large insulating area 64. Both the circular insulating band 67 and the large insulating area 64 are portions of the substrate 61 where the pattern metal has been removed.

Upper and lower (as viewed in FIG. 3) semicircular ring shaped separating regions 66 and 67, where the conductive metal has been removed, separate the inner and outer patterns. The upper separating region 66 has a greater radius from the center of the substrate 61 than the lower separating region 67. In addition, the upper separating region extends though slightly less than 180°.

Connecting the upper and lower separating regions 66 and 67 are right and left separating regions. The right separating region as viewed in FIG. 3 is a rather thin separating region filled with an insulating material 68. The left separating region is an outwardly extending V-shaped region also filled with an insulating material 69. The insulating materials 68 and 69 are added to raise the left and right separating regions to the level of the metallic conductors so that brush passage over the right and left insulating regions is smooth.

An aperture 70 passes through the center of the substrate 61 of the commutator disc illustrated in FIG. 3. It is through this aperture that the stud 11 passes. The aperture 70 is long and has semi-circular ends so that the commutator disc can be moved back and forth as the guide block moves back and forth in the manner heretofore described. Preferably, the longitudinal axis of the aperture 70 is coincident with the longitudinal axis of the V-shaped insulating region on the left of FIG. 3.

It will be appreciative that as the commutator disc is moved back and forth by the guide block-guide block bracket action, the points where the brushes 31 contact the surface of the commutator ring vary. It is this variation that creates switch adjustment. Specifically, as the brushes move back and forth relative to the commutator disc, the point of crossing the V-shaped insulating region 69, when the commutator disc rotates, changes. Because of this change, the length of insulating region over which the brush must pass changes. It is this variation in stop space length that varies the cyclic point of motor turn off to allow the coasting distance to be adjusted when the switch is incorporated in a continuous orbit of travel file cabinet. That is, the point of brush contact with the insulating region is related to the turn off point of the driving motor. And the turn off point of the driving motor controls tray. Finally, because tray coasting is related to the alignment of the trays in the access opening, the V-shaped insulating region controls the alignment of the trays in the access opening. Hence, by varying the point of contact between the brush and the commutator disc, tray alignment adjustment is provided.

FIG. 4 illustrates a commutator disc having an alternative conductive pattern suitable for use in the invention. The substrate 71 of the commutator disc illustrated in FIG. 4 is flat and circular. Outer, center, and inner cylindrical conductive patterns 73, 75, and 77 are located on the surface of the substrate. The outer conductive pattern 73 is separated from the edge of the substrate by a narrow insulating band 74, and the center conductive pattern 75 is separated from the outer conductive pattern 73 by a narrow insulating band 76. The inner conductive pattern 77 is separated from the center conductive pattern by a

narrow insulating ring 78, and from the center of the disc by a large circular insulating region 79. Hence, all three patterns are co-axial but separated. All three insulating rings 74, 76, and 78 and the circular insulating region 79 are portions of the substrate 71 from which metal pattern material has been removed.

The inner and outer patterns are continuous. However, the center pattern is split on the left and on the right as viewed in FIG. 4 to form two semicircular portions. The upper portion is slightly less than 180° and the lower portion is slightly greater than 180°. The right split is rather thin and is filled with an insulating material 81 to raise the split to the level of the conductive pattern. The left split is an outwardly extending V-shaped split that is also filled with an insulating material 83 to raise the split to the level of the conductive patterns. As with FIG. 3 the insulating materials 81 and 83 are merely added so that the brushes pass over the splits in a smooth manner. Smoothness is desired because it prevents brush wear and undesirable arcing.

As with FIG. 3, the commutator disc in FIG. 4 has a long aperture 85 with semicircular ends. The aperture allows the disc to fit over the stud 11 and be moved back and forth. Preferably, the longitudinal axis of the aperture 85 is coincident with the longitudinal axis of the V-shaped insulating region. As with the embodiment of FIG. 3 the V-shaped element of the embodiment illustrated in FIG. 4 allows the switch "stop space" to be adjusted.

It will be appreciated from the foregoing description that a rather uncomplicated switching apparatus is provided. Rather than moving one disc with respect to another to adjust the stop space when a switch is utilized in a continuous orbit of travel filing cabinet mechanism, only the simple adjustment of moving a commutator disc back and forth with respect to a brush holder is required. Hence, the invention is less complicated to adjust than prior art inventions. In addition, the use of a single commutator disc as opposed to a pair of commutator discs makes the invention more economical than prior art inventions of the type illustrated in U.S. Patent 3,198,894.

It would be appreciated by those skilled in the art and others that the location of the conducting patterns illustrated in FIGS. 3 and 4 is merely illustrative. Various other conductive configurations can be utilized as determined by the system in which the invention is to be used. Hence, the invention can be practiced otherwise than in specifically described herein.

What is claimed is:

1. An adjustable rotary switch comprising:
a stud having a longitudinal axis;
a brush holder mounted on said stud;
a plurality of brushes held in said brush holder and extending outwardly from one side of said brush holder;
a commutator disc mounted on said stud for rotation with respect to said brush holder;
a conductive pattern located on the face of said commutator disc;
said conductive pattern facing and being in contact with the brushes of said brush holder; and
an adjustment means for laterally moving said commutator disc with respect to the longitudinal axis of said stud so that the point of contact between said brushes and said conductive pattern can be varied.
2. An adjustable rotary switch as claimed in claim 1, wherein a portion of said conductive pattern is broken by a V-shaped insulating region.
3. An adjustable rotary switch as claimed in claim 2, wherein said V-shaped insulating region extends outwardly from the center of said commutator disc.
4. An adjustable rotary switch as claimed in claim 3, wherein said V-shaped insulating region is raised to the level of the conductive pattern.
5. An adjustable rotary switch as claimed in claim 4, including a second region of insulating material located

on the face of said commutator disc at a point approximately diametrically opposed to said V-shaped insulating region.

6. An adjustable rotary switch as claimed in claim 5, wherein said commutator disc has a long aperture having semicircular ends formed in its center through which said stud passes and wherein the longitudinal axis of said V-shaped insulating region is coincident with the longitudinal axis of said aperture.

7. An adjustable rotary switch as claimed in claim 6, wherein said conductive pattern comprises two conductive regions formed of continuous ring-shaped sections, said V-shaped insulating region separating said sections at a predetermined point.

8. An adjustable rotary switch as claimed in claim 8, wherein said conductive patterns comprises three ring-shaped regions, two of said ring-shaped regions being continuous and the third ring-shaped region being broken at one point by said V-shaped insulating region and at another point by said second insulating region.

9. An adjustable rotary switch as claimed in claim 1, wherein said adjustment means comprises:

a guide block fixedly but rotatably attached to said stud;
a guide block bracket mounted on said disc so as to co-act with said guide block; and
means to vary the lateral relationship between said guide block and said guide block bracket.

10. An adjustable rotary switch as claimed in claim 9, wherein said means to vary the relationship between said guide block and said guide block bracket comprises an adjustment screw that is fixed to, but rotatably mounted in said guide block bracket and turns into threads located in said guide block.

11. An adjustable rotary switch as claimed in claim 10, including a sprocket rotatably mounted on said stud and fixedly attached to said guide block.

12. An adjustable rotary switch as claimed in claim 11, wherein a portion of said conductive pattern is broken by a V-shaped insulating region.

13. An adjustable rotary switch as claimed in claim 12, wherein said V-shaped insulating region extends outwardly from the center of said commutator disc.

14. An adjustable rotary switch as claimed in claim 13, wherein said V-shaped insulating region is raised to the level of the conductive pattern.

15. An adjustable rotary switch as claimed in claim 14, including a second region of insulating material located on the face of said commutator disc at a point approximately diametrically opposed to said V-shaped insulating region.

16. An adjustable rotary switch as claimed in claim 15, wherein said commutator disc has a long aperture having semicircular ends formed in its center through which said stud passes and wherein the longitudinal axis of said V-shaped insulating region is coincident with the longitudinal axis of said aperture.

17. An adjustable rotary switch as claimed in claim 16, wherein said conductive pattern comprises two conductive regions formed of continuous ring-shaped sections, said V-shaped insulating region separating said sections at a predetermined point.

18. An adjustable rotary switch as claimed in claim 16, wherein said conductive patterns comprises three ring-shaped regions, two of said ring-shaped regions being continuous and the third ring-shaped region being broken at one point by said V-shaped insulating region and at another point by said second insulating region.
